Letters Patent No 766. Dated Feb. 12. 1856.

The schedule referred to in these Letters Patent, and making part of the same.

To all whom it may concern,

Be it known that we, Samuel Pierce, & Sanford Burnam, of Troy, in the County of Rensselaer, & State of New York, have invented or produced a new & original design of Cook Stove, which we call the "Magnet," & we do hereby declare that the following is a full, clear, & exact description of the same, reference being had to the annexed perspective drawing, making a part of this specification.

The ornamental design of our cook stove, consists of the ornamental borders (a & b) & panel ornament (c) arranged upon the jamb A. In the ornamental work (d,d) arranged upon the oven door B. The front or fire doors of the front plate C, are ornamented upon the panels of moldings with the ornaments (e & f) of raised panel (g). D. is the hearth plate, with an ornamental border (h). E. is the top plate with molding (i) around the edge. F. is the bottom plate molding.

Having thus described our new
